US00D615025S

(12) **United States Design Patent**
Ma et al.

(10) **Patent No.:** **US D615,025 S**
(45) **Date of Patent:** **** May 4, 2010**

(54) **TIRE**

(75) Inventors: **Jinlin Ma**, Dongying (CN); **Xuejun You**, Dongying (CN); **Yongtao Ye**, Dongying (CN)

(73) Assignee: **Shangdong Yongtai Chemical Group Co., Ltd.**, Dongying Shangdong (CN)

(**) Term: **14 Years**

(21) Appl. No.: **29/262,456**

(22) Filed: **Jun. 30, 2006**

(30) **Foreign Application Priority Data**

Dec. 31, 2005 (CN) 2005 3 0136686

(51) **LOC (9) Cl.** **12-16**

(52) **U.S. Cl.** **D12/554**

(58) **Field of Classification Search** **D12/505-567; 152/209.1, 209.12, 209.18, 209.25**
See application file for complete search history.
